UNITED STATES PATENT OFFICE.

CHARLES P. COTTRELL, OF WESTERLY, RHODE ISLAND, ASSIGNOR TO C. B. COTTRELL & SONS COMPANY, OF NEW YORK, N. Y., AND STONINGTON, CONNECTICUT, A CORPORATION OF NEW JERSEY.

SHEET-DELIVERY MECHANISM FOR PRINTING-MACHINES.

SPECIFICATION forming part of Letters Patent No. 699,867, dated May 13, 1902.

Application filed November 27, 1901. Serial No. 33,871. (No model.)

To all whom it may concern:

Be it known that I, CHARLES P. COTTRELL, a citizen of the United States, and a resident of Westerly, in the county of Washington and State of Rhode Island, have invented a new and useful Improvement in Sheet-Delivery Mechanism for Printing-Machines, of which the following is a specification.

The object of this invention is to provide in a convenient manner in a printing-machine for the delivery of the printed sheets with either side upward, as may be desired; and to this end the invention consists in certain novel combinations of parts, hereinafter described and claimed, including an oscillating fly-frame for the delivery of the sheets with their freshly-printed sides downward and endless chains and attached grippers for their delivery with their freshly-printed sides upward.

Figure 1 is a side view of parts of a two-revolution cylinder printing-machine having applied to it for interchangeable use an oscillating fly delivery-frame and endless gripper-carrying delivery-chains according to my invention; Fig. 2, a section taken parallel with Fig. 1 of the cylinder, the fly-frame, and parts of the endless-chain delivery devices; Fig. 3, a transverse sectional view taken in front of the cylinder.

Similar characters of reference designate corresponding parts in all the figures.

A is the impression-cylinder, which is mounted in the usual or in any suitable manner in bearings on the main framing B of the machine.

R is the receiving-table for the delivered printed sheets, supported in stands E E' on the framing B at a level below the upper part of the cylinder A and at a distance in front thereof greater than the length of the sheets.

The cylinder A is fitted with the usual grippers, (not shown,) which take the sheets to be printed from the feed-table C and from which the printed sheets are stripped by the usual strippers a, said strippers guiding the sheets between the tape-rollers b c, the shafts b' c' of which run in bearings in brackets D, mounted on the journal-boxes g* of the cylinder-shaft g.

d represents carrying-tapes arranged between the cylinder and the receiving-table

and running on the rollers b and on rollers e on a shaft e', which is supported in the stands E. The tape-rollers b and tapes d derive motion from a gear f on the cylinder-shaft g through a gear h on the roller-shaft b' and an intermediate gear i, which turns freely on a fixed stud j, carried by one of the brackets D, and which gears with f and h. The brackets D, stud j, and shaft b' being carried by the boxes g* of the cylinder-shaft, the gear i always remains in gear with the gears f and h. The upper runs of the tapes d travel in a forward direction away from the cylinder. The gear h, which runs constantly, is loose on the shaft b', but is capable of engagement therewith by means of a friction clutch-disk k, Fig. 3, which is fast on the shaft. The engagement of said shaft b' with and its disengagement from said gear h are effected by a slight longitudinal movement of said shaft in opposite directions to bring the friction-disk k into or out of contact with the gear h. This movement is provided for by means of a grooved cam F (see Fig. 3) on the cam-shaft G, which also carries the cam H for operating the fly-frame, as will be hereinafter described, the said shaft G making one revolution for each impression. This cam F operates through a short rock-shaft l, a rod m, and an elbow-lever n, which is forked at its upper end to embrace a grooved collar b* on the shaft b', said rock-shaft working in fixed bearings l' on the main framing B and having one arm l², which engages with the groove of the cam F, and another arm l³, which is connected by the rod m with the lower arm of the elbow-lever n, said lever working on a fixed fulcrum n' on the framing B. The throw of the cam F and the lengths of the arms l² l³ of the rock-shaft l and of the two arms of the elbow-lever n should be so proportioned that the longitudinal movement of the shaft b' should not be sufficient to displace the rollers b b' from the rollers c c. It is obvious that the said longitudinal movement requires to be extremely slight. The engagement of the shaft b' with the gear h is also provided for by a spring 30, (see Fig. 3,) which is applied between the collar b* and the adjacent bearing of said shaft and which acts to press the friction-disk k in contact with the gear h.

I is the rock-shaft of the fly delivery-frame,

and o the fly-fingers attached thereto. This fly delivery-frame, except as to the position of the rock-shaft, resembles fly-frames commonly used in printing-machines for delivering the printed sheets. The bearings for said rock-shaft in the stands E are situated at a distance forward of the cylinder A beyond the forward tape-carrying rollers e , which rollers are at a distance from the cylinder greater than the length of the printed sheets. The fly-fingers o are so spaced that they may intervene between the carrying-tapes d and between the rollers e . The rock-shaft I and the rest-bar o' , provided in the brackets D for the ends of the fly-fingers, are at such elevations that when the frame is thrown backward, as shown in Figs. 1 and 2, with the fingers resting on said bar o' the fingers will be below the upper runs of the tapes d . Sheet-stops x are provided on the fingers o of the fly-frame, said stops being slid over the said fingers and secured thereon by binding-screws y , providing for their adjustment lengthwise of the fingers.

25 The means for producing the oscillating movement of the fly-frame may be and are represented as substantially like those commonly used in printing-machines, as I will now briefly describe.

30 The rock-shaft I is furnished at one end with a toothed sector J , Fig. 1, which gears with a toothed rack-bar p , which derives a longitudinal reciprocating motion from the cam H , before mentioned, the said rack-bar 35 being connected with one arm of an elbow-lever K , which works on a fulcrum q , fixed on the framing, and the other arm of which is connected by a rod q' with a lever L , which works on a fixed fulcrum q^2 on the framing, 40 the said lever L being provided with a roller q^3 , which is kept in contact with the cam H by a spring q^4 , applied between the lever L and a suitable fixed bearing q^5 . The toothed rack on the bar p is kept in gear with the toothed sector J by a bearing-roller p' , applied behind said bar on a stand affixed to the framing.

45 For the purpose of suspending the action of the fly-frame and holding it back, with its fingers o in the inoperative position, (shown in Figs. 1 and 2,) between the tapes and below the upper runs thereof, a detent, represented as a gab-hook 25, pivoted to the frame B , is provided to engage with a stud or projection 50 on the lever K , and so lock said lever in a position to hold back the lever L positively beyond the operative reach of the cam H . The fly-frame is to be thus held back whenever the endless-chain delivery is to be used.

55 60 M is one of the two gripper-chains which carry the grippers s t and are so arranged above the receiving-table R that they may take the sheets from the endless tapes d and deposit them on the said table with the last-65 printed side upward. These chains being both alike and such gripper-carrying chains being common in sheet-delivery apparatus I

have thought it sufficient to represent one of them. The said chains are carried above the level of the tapes d on the sprocket-wheels N , which turn on fixed studs v , carried by the stands E , and on sprocket-wheels N' , which turn on fixed studs v' , carried by the stands E' , and between the said sprocket-wheels N and those N' the said chains are supported in straight guides P , carried by the stands E E' . Said stands, chains, and guides are at a distance apart laterally greater than the width of the fly-frame, that the fingers o of the latter may pass between them. The sprocket-wheels N , on which the rearward portions of said chains run, are a short distance in rear of the tape-carrying shaft e' and rollers e . For giving motion to said chains the sprocket-wheels N have attached to them spur-gears Q , which gear with two spur-gears S on a shaft S' , which turns in bearings in the stands E and which has on one end a bevel-gear S^2 , gearing with a bevel-gear u' on an upright shaft u , which works in bearings u^* on the outside of the framing B and stand E . This shaft u has on its lower end a bevel-gear u^2 , which gears with a bevel-gear which is carried by a spur-gear u^3 , (concealed by said spur-gear u^3 in Fig. 1,) turning on a fixed stud u^5 in a stand u^6 on the lower part of the framing B . The spur-gear last mentioned gears with a spur-gear T , which is carried by a spur-gear T' , turning on a fixed stud T^2 , affixed to the framing B . The gear T' gears with and is driven by a gear U , Fig. 1, on the cam-shaft G , and so imparts motion through the gears T , the spur-gear u^3 and its attached bevel-gear, the gear u^2 , shaft u , and gears u^* S^2 to the sprocket-wheel-driving shaft S' .

50 The grippers s t , hereinbefore mentioned as carried by the endless chains, consist of any suitable number of members s and corresponding members t , which operate between the carrying-tapes d . The gripper members s consist of jaws rigidly attached to a bar s' , which is rigidly attached to the two carrying-chains, and the members t are jaws fastened on a spindle t' , which is pivoted into the carrying-chains and which is furnished near one end with a tappet t^2 for operation against stationary cams w w' , which are affixed to the sprocket-wheel studs v v' for the purpose of opening the grippers at the proper times to receive the printed sheets from the tapes d and to release them for deposit on the table. The gripper members t are normally closed by springs applied in the usual or any suitable manner.

55 60 To explain further the operations of the two deliveries, I will first suppose that the fly-delivery is to be used for delivering the sheets with the last-printed side downward. In this case either the grippers, with their bar s' and spindle t' , should be removed from the chains M or the gears T T' removed from the stud T^2 . If the grippers, with their bar and spindle, be removed, the chains will run inoperatively; but if said gears only be removed to

stop the running of the chains the latter should be moved to bring the grippers to a position over the sprocket-wheels N , where their bar and spindle will be out of reach of the fly-frame. For this operation of the fly-delivery the shaft b' , which drives the tapes, is disconnected from the cam F , which may be done by taking out the pin which connects the rod m with the rock-shaft arm b , leaving the said shaft b' under the control of the spring 30, which keeps the gear h constantly coupled with the shaft b' by the friction-disk k and the tapes constantly running. The hook 25 being then thrown back from the stud 26 on the lever K to a position of rest against a projection 27 on the frame to leave the fly-operating mechanism free to the operation of the cam H , and the printing-machine being then set in operation, each printed sheet taken on by the carrying-tapes d , which are then in motion, will be carried forward, printed side upward, over the fly-fingers, while the latter are thrown back to the position shown in Figs. 1 and 2 until the front edge strikes the stops x . The cam H then by its movement permits the fly-frame to be thrown forward by the action of the spring q^4 on the lever L to turn over the sheet and deposit it on the table R . After this deposit of the sheet the fly-frame is swung back by the action of the cam to its position of rest on the bar o' , ready for the reception of another sheet to be delivered on the table R in the same manner. To change from the use of the fly-delivery to the use of the endless-chain delivery for the delivery of the sheets with their printed side upward, the sheet-stops x are removed from the fly-fingers or set forward thereon beyond the tapes, and the fly-operating mechanism is brought to the position shown in Fig. 1, in which the fly-frame is held back between the tapes and the lever L beyond the operative reach of the cam, and the said mechanism is so locked by bringing the detent 25 into engagement with the lever K . The connection between the cam F and the shaft b' is also restored. If the grippers had been removed from their carrying-chains M , they should now be replaced and the chains be so adjusted relatively to the impression-cylinder and the mechanism for operating the tapes d that the grippers arrive in such position below the sprocket-wheels N , where they are opened by the cam w just as the sheet carried by the tapes has its front edge brought to the grippers. This adjustment of the chains may be effected by turning the shaft S' by a hand-crank or equivalent device, the gears T' being at the time removed from the stud T^2 . The latter gears having been replaced in gear with U and u^3 , respectively, and the machine having been set in motion, each sheet taken from the cylinder on the tapes d , with its last-printed side upward, is carried by the latter till its front edge reaches the grippers, which are then held open by the cam w , and at this

moment by the action of the cam F the tape-roller shaft is disengaged from its driving-gear h and the movement of the tapes is arrested. The grippers then immediately escaping from the cam w close on the sheet, which is then carried forward over the table R until the grippers arrive at the cam w' , on striking which they open and liberate the sheet, which then drops to the table with the last-printed side upward. 75

On reference to Fig. 1 it will be seen that the chain-driving gears U and T' are shown eccentric to their shafts. This eccentricity may not be necessary, but I consider it preferable in order that the chains may have a slower motion at the time of opening the grippers to drop the sheets upon the receiving-table. It may also be seen on reference to Figs. 1 and 2 that the tapes and the gripper-chains are represented with a downward inclination in a forward direction. I consider this inclination desirable to facilitate the carrying forward of the sheets. 85

Except as to what is hereinafter claimed, 90 the devices hereinabove described are subject-matter of my application, Serial No. 73,151, for United States Patent filed August 24, 1901.

What I claim as my invention is— 95

1. In a printing-machine, the combination of a rotary impression-cylinder, a fly delivery-frame and mechanism for operating the same, a chain delivery-carrier consisting of chains and attached grippers, tapes common to said fly-frame and to said carrier for receiving the printed sheets from said cylinder and presenting them either to said fly-frame or said carrier and means for securing the said mechanism with the fly-frame in an inoperative 100 position between the tapes and below the operative portions thereof, substantially as and for the purpose herein described. 105

2. In a printing-machine, the combination of a rotary impression-cylinder, a fly delivery-frame and a rock-shaft for said frame, a chain delivery-carrier consisting of chains and attached grippers, tapes common to said fly-frame and to said carrier for receiving sheets from the cylinder and presenting them either 110 to said fly-frame or to said carrier, a toothed sector on said rock-shaft, a rack-bar engaging with said sector, a rotary cam and operating mechanism between said cam and said rack-bar, and a detent applied to said mechanism 115 for holding it out of operative relation to said cam with the fly-frame stationary below the operative portions of the tapes, substantially as herein described. 120

In testimony that I claim the foregoing as 125 my invention I have signed my name, in presence of two witnesses, this 25th day of November, A. D. 1901.

CHARLES P. COTTRELL.
